HOPPER CAR

Allen E. Ostrander, Larchmont, N. Y., Robert W. Joy, Berwick, Pa., and Adolph Kassler, New York, N. Y., assignors to American Car and Foundry Company, New York, N. Y., a corporation of New Jersey

Application August 1, 1935, Serial No. 34,200

19 Claims. (Cl. 105—249)

This invention relates to new and useful improvements in railway cars in general and in particular to improvements in hopper cars.

One of the objects of the invention is the construction of a light weight car utilizing as few parts as is economically possible.

Another object of the invention is the construction of a car designed for rotary dumping in which the side stakes and inclined upper portion 10 of the side walls are pressed from a single piece of plate metal.

Another object of the invention is the provision in a railway car of a new and improved bolster and manner of connecting it to the center sill.

Another object of the invention is the provision 15 of a car which is completely self discharging due to the manner of connecting the hoppers to the center sill and side sills.

Another object of the invention is the provision 20 in a railway car of a new and improved light weight center sill which may be easily fabricated of plate members.

A further object of the invention is the provision 25 of a new and improved side sill for hopper cars.

A further object of the invention is the provision of a new and improved cast hopper door frame.

A still further object of the invention is the provision 30 of an extremely strong and rigid cross ridge construction for hopper or like cars.

These and other objects of the invention will be apparent to one skilled in the art from a study of the following description taken in conjunction 35 with the accompanying drawings in which:

Figure 1 is a plan view, partly in section, of a hopper car constructed in accordance with the present invention;

Fig. 2 is a side view of the car taken on line 40 2—2 of Fig. 1;

Fig. 3 is an enlarged sectional view of the central part of the car taken on line 3—3 of Fig. 1;

Fig. 4 is an enlarged side view of a hopper;

Fig. 5 is a sectional view of the hopper taken on 45 line 5—5 of Fig. 3;

Fig. 6 is a sectional view of the car, showing the cross-bearer in elevation and taken on line 6—6 of Fig. 3;

Fig. 7 is a sectional view of the cross-bearer taken on line 7—7 of Fig. 6;

Fig. 8 is a detail sectional view showing the connection of the ridge sheets to the side stake and sheet and taken on line 8—8 of Fig. 3;

Fig. 9 is a perspective view of the cross-bearer 50 plate;

Fig. 10 is a perspective view of a modified form of side plate for the center of the car;

Fig. 11 is a perspective view showing the connection between the side sheet, hopper sheet and side sill;

Fig. 12 is a sectional view of one end of the center sill taken on line 12—12 of Fig. 2;

Fig. 13 is an enlarged sectional view of one end 10 of the car and taken on line 13—13 of Fig. 12;

Fig. 14 is an end elevation of the center sill 15 showing the means for carrying the draft gear;

Fig. 15 is a sectional view taken on line 15—15 of Fig. 13;

Fig. 16 is a sectional view taken on line 16—16 20 of Fig. 2 and Fig. 17 and showing the means of joining the bolster plate to the center sill and side plate;

Fig. 17 is an elevational view of the car bolster;

Fig. 18 is a sectional view taken on line 18—18 25 of Fig. 17 and shows the manner of connecting the side sheets;

Fig. 19 is an enlarged sectional view taken on line 19—19 of Fig. 17 and showing the bolster connection to the center sill;

Figs. 20, 21 and 22 are sectional views showing 30 details of the bolster construction and are taken on lines 20—20, 21—21, and 22—22, respectively, of Fig. 17;

Fig. 23 is a perspective view showing the relation of the bolster lower casting and center sill;

Fig. 24 is a perspective view of the bracing means connecting the bolster plate and center sill;

Fig. 25 is a side elevation of the center sill;

Fig. 26 is a plan view of the center sill shown in 35 Fig. 25;

Fig. 27 is a view showing the bottom of the center sill;

Fig. 28 is a perspective view showing the bolster plate applied to the center sill;

Fig. 29 is a perspective view of the side sheet as altered for use at the bolster;

Fig. 30 is an elevational view of the side sill;

Fig. 31 is a plan view of the side sill;

Figs. 32, 33 and 34 are sectional views taken on 40 lines 32—32, 33—33 and 34—34, respectively, of Fig. 30;

Fig. 35 is a perspective view showing the manner of joining the hopper and side sill;

Fig. 36 is a perspective view of one-half of the 50 car with the top rail removed;

Fig. 37 is a perspective view of the shed plate or ridge sheet;

Fig. 38 is a perspective view of a modified form 55 of center sill.

Referring now to the drawings it will be seen that the car illustrated is of the maximum capacity type and that the side wall is the main load carrying member. The car in general consists of trucks A supporting the bolsters B, which are connected to the center sill C by suitable bracing means. The side wall D is formed of a number of plates fastened together so as to form the side stakes and this wall is attached to the bolsters, hopper E, slope sheets F and cross ridge construction G to form a rigid load carrying unit.

The various component parts of the car as mentioned above will now be referred to and described in detail with the center sill construction being considered first. The center sill C, as shown by the various cross sectional views and Figs. 25-27 inclusive, is formed of two plates 36 and 38 each having a vertical lower portion, an inwardly inclined intermediate portion 40, and a vertical top flange 42. These flanges may be joined by rivets as shown or be welded to secure the plates together as well as exclude moisture from the joint. Secured to the inner surface of each center sill plate intermediate the bolsters 25 and at the lower edge portions thereof is a rolled angle bar or if desired a pressed angle plate 44 which is spaced from the sill plate by spacers 46. This angle member extends only a slight distance beyond the slope sheets although if desired 30 or necessary it is obvious that it may be extended to the bolster filler casting. Angle members 48 are attached to the outside lower edge portion of the sill plate with their flanges directed outwardly and having fastened thereto 35 bolster cover plate 50 and draft gear retaining members 52 as clearly shown in Fig. 21. These angles extend from the end of the sill casting to a point adjacent the slope sheet and overlap the interior angles. Pressed filler members 54 having flanges for attachment to the sill are placed 40 in the central portion of the sill and together with the bolster filler casting and end casting 56 act to brace and stiffen the center sill, thus forming a rigid light weight center sill. As shown in 45 Fig. 12, the end casting is of somewhat usual design having a coupler carrying portion 51 and rearwardly directed flanges 53 for attachment to the sill adjacent to cheek plates 59. Flanges 60 and 61 are provided conforming in position to 50 the outline of the sill to which they are suitably secured.

The bolster B, as appears clearly in Figs. 17 and 20 to 24, inclusive, is formed of a lower cast portion 62 of truss formation having an interrupted lower chord 64, continuous upper chord 66 of T formation, vertical struts 68 conforming to the sill outline, vertical struts 70 over each side bearing, diagonal ties 72 and web plate 74. The lower chord tapers from the center sill outwardly 60 therefrom and conforms in outline to the lower plate 50 to which it is attached, thus completing the lower chord. The usual body center bearing 76 is supplied below the filler casting 78 which is of standard design with the exception of 65 changes in the external contour to adapt it to the improved center sill, but since these changes are obvious a detailed description thereof is believed unnecessary.

Adjacent each end of the bolster casting the 70 top chord has a portion depressed slightly and with the upstanding flange eliminated in order to accommodate a bar 80 of substantial width that extends between and connects the casting to the side sill. Mounted upon this bar and top chord is a bolster plate having inclined top flanges 82 to

support the slope sheet, end flanges 84 for attachment to the side plates and lower flange 86 for attachment to the casting, bar 80 and side sill of the car. The bolster plate is also attached to the casting by means of rivets passing through the plate and upstanding leg of the top chord, and is also attached to the bar 80 by angle 88. The bracing castings 90 are provided in order to brace the bolster plate as well as to form a more rigid connection to the center sill and compensate for the metal removed by the elimination of the upstanding sill flanges at this point. These bracing castings are formed with a flat plate 92 for attachment to the bolster plate, curved lower flanges 94 for attachment to the center sill intermediate portion and a bracing gusset 96, the lower portion of which is offset slightly to one side for attachment to the upstanding center sill flanges. A connecting gusset 98 joining the brace 96 and face 92 is also provided and it is seen that an extremely strong center brace of cross formation is formed when the two castings are assembled as clearly shown in Figs. 16-19.

The bolster plate is braced and strengthened immediately over the side bearings by angles 100 having one leg attached to the plate and extending down through the top chord of the casting for attachment to the web 74. The other leg of the angle rests against and is fastened to one of the vertical chords of the bolster casting which 30 form the side bearing. An angular or other form plate bracing member 102 is provided which aids in preventing any buckling of the bolster plate on transmitting strains from the side wall to the center or side bearings.

It is thus seen that a strong bolster is formed in which the lower and more complicated portions have been cast, while the upper portion has been formed of rolled plate which for a given weight is much stronger than a casting. This 40 construction also lends itself readily to the use of standard castings for various cars, the differences in design being absorbed by modifications of the pressed plate which may be readily formed to the desired shape or size.

The side sill R of angular formation extends from end sill to end sill and has its inwardly directed flange 104 fastened to the flange 86 and plate 80 of the bolster, while its upwardly directed flange 106 is fastened to the bolster flange 84, thus rigidly securing the sill to the bolster. The flange 104 adjacent each hopper has been bent, by rolling or pressing, to the outline shown in Figs. 34 and 35 in which the lower portion of the flange is inclined in conformity with the hopper side sheet to which it is securely fastened. The hopper side sheet is likewise secured to the upwardly directed flange and there is thus provided a triangular shaped sill of great strength at these points. It is obvious that such a construction forms not only an extremely strong sill, but eliminates any pockets or ledges on which the lading could lodge. Attention is also directed to the fact that the sill may be of triangular formation from bolster to bolster in which case 65 an added strip of metal would be necessary, or the lower portions of the side sheets could be pressed inwardly and perform the same function as does the hopper sheet shown.

The hoppers may be formed of a single pressing 70 but in order to conserve metal they have been shown as formed of a floor sheet 108, outer sloping side sheet 110, which is secured to the side sill as mentioned, and inner vertical side sheet 112 which has its upper edge so formed as to be 75

fitted between the angle 44 and the bottom part of the center sill as shown in Fig. 5. The upper end of the hopper floor sheet 108 is secured to the center sill by angles 114 and corner forming member 116 and is braced by angle members 118 in the usual manner. A hopper is thus provided in which the inner wall is set inward of the center sill wall and the outer wall slopes at a constant angle whereby all material will be discharged from the car.

The hopper door frame 120 is cast in one piece and provided with angular side and bottom portions conforming to the outline of the hopper and, in order that a rectangular door opening may be provided, it is necessary to provide connecting portions 122 of irregular formation as clearly shown. The top part of the frame is provided with an inclined flange 124 on which is integrally formed the hinge lugs 126, one of which is extended some distance from the flange to which it is joined by gusset 128 forming in reality a continuation of the flange.

The cross ridge construction G is formed in the main by three plates, one of which is vertically disposed, with the other two acting as shed plates and inclined toward the hopper frame. The vertically disposed plate 130, Fig. 9, has the central portion notched out to straddle the center sill to which it is attached immediately over a filler 54 by angle member 132. The plate is provided with flanges 134 secured to tie plate 136, top flange 138 and end flanges 140 secured to one leg of angular member 142, the other leg of which is attached to the vertical plate, all as clearly shown in Figs. 6 and 7. The inclined plates 144 are duplicates of each other so that right and left plates are not necessary and each of these plates is provided with an angularly disposed flange 146 for attachment to plate 130 and flanges 148 for attachment to the side walls of the car. The central portion of the plate is notched and flanged in order to fit over and be fastened to the center sill, while the lower edge is adapted to overlie and be secured to the upper door frame member. The corners of the plate 144 are bent or formed in accordance with the side stake contour to be described later.

The ridge construction is braced by means of angular members 150 secured to the vertical plate 130 and provided with outstanding portions to which angles 152 are secured. These angles underlie and are secured to the plates 144 and extend to the door frame gusset 128 to which they are secured. A ridge construction is thus formed which gives exceptional strength while permitting the use of relatively thin plates due to the improved arrangement of parts and the addition of the ridge bracing angles.

The side wall of the car which is the main load carrying member has been formed of a plurality of sheets or plates so fabricated and connected together as to form the wall and side stakes. The wall plates 154 are all similar and have a cross section as shown in Fig. 11 in which the body of the plate is pressed inwardly slightly at 156 a distance sufficient to accommodate the adjoining plate and provide a flush outer surface. The plate has the two securing or riveting portions 158 joined by the U-shaped portion 160 which together may be termed a flanged channel and will thus form with the adjoining plate a box section side stake as clearly shown in Fig. 1. The lower portion 162 of the stake may be part of the plate, but is preferably a small member welded to the stake and hopper side sheet. The

upper portion of the plate is pressed inwardly at 164, then upwardly at 166 and these portions are uniplanar with the exception of the portion at the stake which is offset inwardly, being an extension of the inset 156. Since the flanged channel is intersected by this inwardly and upwardly inclined portion a truncated side stake is formed.

The wall plates at each bolster are identical with the other side wall plates just described except that the lower portion is formed as shown in Fig. 29 in which the U stake is sawed and one leg of the U bent inwardly to provide flange 168 for attachment to the bolster plate which extends to the side wall and takes the place of the metal bent from the stake as shown in Figs. 16 and 17; the bolster plate thus forming a part of the box section stake, as will be apparent. In practice it may be preferable, in order to avoid a double bend of the metal, to eliminate the flange 168 and weld the pressed stake directly to the bolster. The plates at each corner of the car extend inwardly from the bolster to the corner stake in order to provide clearance for the car ladders, and due to their angularity the upper inclined portion gradually vanishes as clearly seen in Fig. 36.

The car as constructed requires a special arrangement at the center of the car as clearly shown in Figs. 1 and 7 and, in order to eliminate two extra sets of dies, a separate stake is used. The stake 170 is of double angle formation with one flange joined to the side wall and the other free flange joined to the flange of the angle 142, thus forming a box section stake similar to the integral stake previously described. A modified form of plate for use at the center of the car is shown by Fig. 10 and gives the same construction as just described with the exception that the double angle 171 is formed integral with one of the plates.

The lower edge of the side plates is fastened to the lower chord or side sill, while the upper inset edge is fastened to the channel form upper chord or top rail 172 which has one flange secured to the plate flange 166, while the other flange is spaced outwardly therefrom substantially in the plane of the side. Pressings 174 are provided at each side stake or wherever needed and as shown are simply plates fastened to the sides and top chord with a rigidifying indentation 176 pressed therein, which indentation has one wall resting upon the inclined portion of the side sheet.

A very rigid side wall is thus formed with integral inside stakes of box section well adapted to withstand the strains incident to dumping the car in a cradle as is very frequently done as well as withstanding the normal bulging strains during transit of the car. The inclined upper portion of the side not only strengthens the car for side thrusts, but forms a smooth shedding surface over which the material will readily slide.

The ends 178 are formed of single plates with the upper portion inset in exactly the same way as the side sheets in order to provide ready discharge of material as well as to give maximum lading capacity, and this inclined portion is connected with the edge portions of the plate by inclined triangular shaped portions 180. The end top chord 182 is similar to the side top chord, with the exception it is turned end to end in order to place the long flange of the channel on the outside of the car in order to give maximum

strength. Channel shaped brace 184 is attached to the end plate and end top chord to prevent any bulging tendency of the central portion of the end plate, while the top chords are rigidly tied together by corner bracket 186.

The slope sheets are formed of plates 188, 190 and connecting strip 192. The plates 188 have the upper and one side edge flanged in order that the plate may be secured to the end and side plates. Plates 190 are flanged at one edge and this flange is provided with offsets to accommodate the pressed side stakes to which they may be welded if desired. It will be noted that in bending these flanges the plate is not bent at right angles, but on a rather large radius, which does not weaken the plate and aids in the discharge of material from the car.

A modified form of center sill is shown in Fig. 38 and this sill is formed of a single plate 193 having an angular top portion 194 and vertical sides 196 to the lower edge of which is attached angles 198. This sill may be strengthened by means of corrugations or indentations 200 pressed in the plate strengthening the angular top part of the sill.

Although the improvements have been shown and described with reference to a single form, it is to be understood that various necessary or desirable modifications may be made without departing from the scope of the invention as defined by the following claims.

What is claimed is:

1. A freight car having bolsters, side wall plates formed with integral channel portions adjacent the bolster ends, additional side wall plates overlapping said channel to form box section side stakes, a part of the lower portion of the stake being omitted and a bolster plate secured to said stake and side wall plates, thereby replacing the portion of the channel omitted and completing the box section stake.

2. A freight car having a bolster plate and a plurality of side sheets, said bolster plate and side sheets being secured together and mutually cooperating to form a box section side stake.

3. A freight car having bolsters, side sheets formed with integral channel portions adjacent the bolster ends, the lower part of the channel being bent back to form a Z section, a bolster plate secured to said Z in such a manner as to complete the channel and additional sheets overlapping and secured to said channel, thereby forming a continuous box section side stake.

4. A freight car having bolsters, side sheets formed along at least one edge with integral channel and Z bar portions, certain elements of which lie in a single plane, a bolster plate secured to the Z portion and extended therebeyond and additional sheets secured to said first named sheets and to said extended bolster plate to thereby form a continuous box section side stake.

5. A freight car having a bolster, a center sill, side sheets on opposite sides of the car, each sheet being formed with an integral channel portion, a bolster plate secured to the center sill and forming a part of each channel portion, additional side sheets overlapping said channel and secured to said first named sheets and bolster plate, thereby forming box section side stakes rigidly tied to the bolster and center sill.

6. A freight car having a center sill, side sheets so formed and connected as to form box section side stakes at their meeting edges, a composite bolster connecting said center sill and

side stakes and formed in part by a metal upper portion, the ends of which form with the side sheets the lower part of said box section stakes, whereby the sides, composite bolster and center sill are rigidly tied together.

7. A freight car having a center sill, side sheets so formed and connected as to form box section side stakes at their meeting edges, a bolster casting straddling and rigidly secured to the center sill, a bolster plate rigidly secured to said casting and extending therebeyond to form with the side sheets the lower portion of said box section stakes, whereby the side sheets and center sill are rigidly tied together.

8. A freight car having box section side stakes, a center sill, a bolster secured to the center sill and comprising in part, a unitary cast portion straddling the center sill and formed with side bearing portions, a bottom cover plate for the bolster arranged intermediate the side bearing portions, a bolster plate extending upwardly from and rigidly secured to said cast portion, and means positioned on either side of the plate to brace and secure the plate to the center sill, said plate extending beyond said side bearings and forming a part of said box section side stakes, whereby the sides of the car and center sill are rigidly tied together.

9. A freight car having a floor, a center sill formed with an upstanding top flange, a composite bolster formed of a lower cast portion having a continuous top member of T formation, lower members secured at their inner ends to the center sill, side bearing members connecting substantially the outer ends of said top and bottom members, a flanged bolster plate attached to said top member and extending thereabove to support the car floor and bracing means on either side of said plate having attachment to said sill flange, top member and plate.

10. A freight car having a floor, side sills, a center sill formed with an upstanding top flange, a composite bolster formed of a lower cast portion having a continuous top member of T formation, lower members secured at their inner ends to the center sill, side bearing members connecting substantially the outer ends of said top and bottom members, a flanged bolster plate attached to said top member and extending thereabove to support the car floor, bracing means on either side of said plate having attachment to said top member, plate and center sill flange, angle bars connected to the top member and plate, and bottom plate means connecting said top member, angle bars, bolster plate flanges and side sills together.

11. A railway hopper car having a center sill formed of two deformed Z plate members, the upwardly extending flanges of which are connected together, while the downwardly extending flanges are spaced apart to thereby form the sill side walls, filler members spaced at intervals along the lower edge of each side wall, hopper side sheets occupying the space between the fillers, longitudinally extending angles positioned between the sill walls and means securing said angles, fillers and hopper sheets to the respective sill wall whereby an unobstructed hopper discharge is obtained.

12. A railway hopper car having a center sill formed of two deformed Z plate members, the upwardly extending flanges of which are connected together, while the downwardly extending flanges are spaced apart to thereby form the sill side walls, filler members spaced at intervals

- along the lower edge of each side wall, hopper side sheets occupying the space between the fillers, longitudinally extending angles positioned between the sill walls, means securing said angles, 5 fillers and hopper sheets to the respective sill wall whereby an unobstructed hopper discharge is obtained and additional angles positioned exterior of the sill beyond the hopper zone, thereby leaving the inner part of the sill unobstructed 10 for the reception of draft gear.
13. A railway hopper car having slope sheets, side walls, an end plate having a flange supporting the slope sheet, said end plate extending between and being secured to the side plates with 15 the major portion lying in substantially a single plane, the upper central portion thereof being deflected inwardly and upwardly, and triangular shaped portions connecting said deflected portion with the major portion.
14. In a freight car, bolsters formed of a cast lower portion and a plate metal upper portion, and side wall plates, the bolster upper portions and said side wall plates being secured together and mutually cooperating to form box section 20 side stakes.
15. In a freight car, bolsters, each including a plate metal member, side wall plates relatively so formed and connected as to provide inside stakes of box section form for the major portion 30 of their length, the lower portions of said side wall plates and said plate metal member being secured together and mutually cooperating to provide a box section constituting the lower portions of said stakes.
16. A freight car having box section side stakes, a center sill, a bolster secured to the center sill and comprising in part, a cast portion straddling the center sill and formed with side bearing portions, a plate metal member extending upwardly 40 from the bolster and rigidly secured to the cast portion, and means secured to said plate metal member for bracing and connecting said member to the center sill, said plate metal member extending laterally beyond the side bearing portions 45 and forming a part of said box section side stakes whereby the sides of the car and the center sill are rigidly tied together.
17. A freight car having a center sill, side sheets so formed and connected as to provide 50 box section side stakes extending substantially from the upper to the lower edge portions of said sheets at their connected portions, a com-
- posite bolster connecting said center sill and side stakes and formed in part by a plate metal portion section, the end portions of which cooperate with the side sheets to provide the lower portions of said box section stakes whereby the 5 sides of the car, the composite bolster and the center sill are rigidly tied together.
18. In a railway car side wall construction, a top cord, a bottom cord, and a plurality of plates connecting said cords, at least some of the plates being formed with a major portion positioned in substantially a single plane, a minor portion extending inwardly and upwardly therefrom, a flanged channel formed in each of said major and minor portions, said channel having a web substantially parallel to the plane of the major portion and having its flanges oppositely directed and offset inwardly from said major and minor portions substantially the thickness of the adjacent plate, and the upper end of said channel web being 10 also offset inwardly a like amount from said web, said offset flanges and web being adapted to receive and be secured to the edge of the adjoining plate whereby a smooth outside wall surface is provided reinforced by a truncated side stake of 15 substantially box section.
19. In a railway car side wall construction, a top cord, a bottom cord, and a plurality of plates connecting said cords, at least some of the plates being formed with a major portion positioned 30 substantially in a single plane, a minor portion extending inwardly and upwardly therefrom and including a vertically extending top edge substantially parallel to the plane of the major portion but offset inwardly therefrom, a flanged 35 channel formed along one side edge of certain of said plates and in each of said major and minor portions, said channel having a web substantially parallel to the plane of the major portion and having its flanges oppositely directed and offset inwardly from said major and minor portions substantially the thickness of the adjacent plate, and the upper end of said channel web being 40 also offset inwardly a like amount from said web, said offset flanges and web being 45 adapted to receive and be secured to the edge of the adjoining plate whereby a smooth outside wall surface is provided reinforced by a truncated side stake of substantially box section.
